UNITED STATES PATENT OFFICE.

CHARLES L. LEE, OF DAYTON, OHIO, ASSIGNOR TO GENERAL MOTORS RESEARCH CORPORATION, OF DAYTON, OHIO, A CORPORATION OF DELAWARE.

ASSEMBLY FIXTURE.

Application filed April 2, 1923. Serial No. 629,404.

To all whom it may concern:

Be it known that I, CHARLES L. LEE, a citizen of the United States of America, residing at Dayton, county of Montgomery and State of Ohio, have invented certain new and useful Improvements in Assembly Fixtures, of which the following is a full, clear, and exact description:

This invention relates to heat interchange apparatus having heat dissipating means such as for example an engine cylinder, provided with cooling ribs or fins for dissipating heat from the cylinder walls.

More particularly the invention relates to the manufacture of finned vessels or cylinders in which the vessel and the fin material are separately formed and are joined together by a suitable bonding operation. Such process is disclosed in the copending application of Charles F. Kettering, Serial No. 514,014, filed November 9, 1921. This application discloses means for providing an engine cylinder with a large number of thin fins of high heat conductivity such as copper. The fins are preferably formed by folding a strip of thin sheet material so as to provide a continuous strip of fins or fin loops. These fin loops are sufficient in number so that when wrapped about a cylinder, the ends of the strip will meet and the fins will be closely arranged and equally distributed around the cylinder. This fin material is temporarily held in position by suitable clamping means with a sheet of bonding material located between the cylinder and the portions of the fin loops which are to be attached to the cylinder. Then this assembly is subjected to a heating operation to produce a permanent bond between the cylinder and fins.

The aims of this invention are to provide apparatus for facilitating the assembling of the fin material, bonding material and the cylinder in temporary relation so that when the assembly is placed in the heating furnace the parts will be permanently bonded together in the proper relation. More particularly it is an object to provide a fixture which will locate the fin material and the cylinder in correct relation to each other while the clamping means is applied to hold the bonding material and the fin material temporarily in place.

Further objects and advantages of the present invention will be apparent from the

following description, reference being had to the accompanying drawings, wherein a preferred form of embodiment of the present invention is clearly shown.

In the drawings:

Fig. 1 is a perspective view showing one form of assembling apparatus, without the cylinder assembly.

Fig. 2 is a perspective view of the cylinder assembly and assembling fixture.

Fig. 3 is a plan view of the assembling fixture showing the cylinder in position but without the fin material and bonding material being shown.

Fig. 4 is a sectional view taken on the line 4—4 of Fig. 3.

Fig. 5 is a perspective view of a modified form of the invention showing the cylinder and bonding material in position.

Fig. 6 is a perspective view of the fin material for which the fixture shown in Fig. 5 is especially adapted.

Fig. 7 shows a perspective view of a group of locating pins.

Fig. 8 is a perspective view of a group of spacing blocks.

Fig. 9 is a perspective view of a fin clamp.

Fig. 10 is a side elevation of the fixture shown in Fig. 5 with the cylinder assembly in position.

Fig. 11 is a top plan view of the apparatus shown in Fig. 10, a portion being broken away for the sake of clearness.

Fig. 12 is a sectional view taken on the line 12—12 of Fig. 10.

Referring particularly to Figs. 1 to 4 inclusive, the apparatus comprises a base 20 supporting a cylindrical post 21 having a flange 21^a which is received by a cylindrical recess 22 provided in the cylinder support 23.

Support 23 is provided with a hollow column 24 coaxial with the recess 22 and journaled upon the post 21. The column 24 is adapted to fit within the cylinder 25 having a base 26, one corner of which is received by a locating fixture 27 attached by screws 28 to the base 23. In this manner the cylinder is located in a predetermined relation to the cylinder support.

The apparatus includes means for positioning and supporting a sheet of bonding material and also for supporting and positioning the fin material with respect to the cylinder. This means includes two half-rings 30 and 31 adapted to fit around the

cylinder 25. Half-ring 30 is pivoted at 32 upon the cylinder support 23 and provided with a notch 33 adapted to be received by a pin 34 carried by the support 23. A segment gear 35 attached to half-ring 30 engages a segment gear 36 attached to the half-ring 31 which is pivoted at 37 upon the support 23. Half-ring 31 is provided with a notch 38 adapted to be received by the pin 34. Movement of one of the half-rings causes the movement of the other through the gearing. When the half-rings strike against the pin 34 the half-rings will be spaced from the exterior wall of the cylinder 25 for the purpose to be described later. The half-rings 30 and 31 are held in position shown in Fig. 3 by means of the fork lever 40 pivoted at 41 upon the support 23 and provided with lugs 42 and 43 adapted to prevent the outward movement of the half-rings 30 and 31 respectively. These half-rings provide means for embracing a sheet of bonding material to be placed around the cylinder and also provides a shelf for supporting the fin material. This shelf is located at a predetermined distance from the base and top of the cylinder.

In order to yieldingly clamp the sheet of bonding material shown at 45 in Fig. 5, and in Fig. 3, about the cylinder each half-ring is provided with an arm 46 pivotally mounted at 47 each arm being yieldingly pressed towards the cylinder by means of a spring 48 bearing against a stop 49. Normally a lug 50 provided on each arm 46 extends inside the inner periphery 51 of each half-ring as shown in Fig. 1. A notch 52 is provided for receiving the lug 50 when the arm is caused to move away from the inner periphery 51. When the lugs 50 are in the position shown in Fig. 1, the arms 46 will bear against the stops 49. When the half-rings are clamped in the position shown in Fig. 3 the lugs 50 will bear against the sheet of bonding material 45 wrapped about the cylinder to hold this material temporarily in place about the cylinder and to prevent it from sliding down along the cylinder.

After the bonding sheet 45 has been secured in position the fin material designated as a whole by numeral 60 in Fig. 2 is placed upon the half-rings 30 and 31 and wrapped about the cylinder 25 and bonding means 45 as shown in Fig. 2. The half-rings 30 and 31 provide for supporting the fin material and for locating it correctly with respect to the upper end of the cylinder.

The fin material and bonding sheet are held temporarily in position by any suitable clamping means such as soft iron binding wires 61. In order to space these wires and hold them temporarily while they are being wrapped about the cylinder and fin material and are being secured by pushing

the ends together, there is provided a block 62 having grooves 63, each adapted to receive a wire 61. This block is pivoted at 64 upon a bracket 65 secured to the base 23. The block is provided with an operating handle 66 and is held at either in operating and non-operating positions shown at Figs. 1 and 4 respectively by means of a spring 67 attached to the bracket 65.

To use this apparatus it is first arranged as shown in Fig. 1, then the cylinder 25 is placed in position over the post 24 with a portion of its base located by the fixture 27. The bonding material is wrapped around the cylinder and held with one hand while the other hand rotates the half-rings 30 and 31 to the position shown in Fig. 2 and the half-rings are held in place by means of lever 40. The fin material 60 is placed upon the shelf provided by the half-rings 30 and 31 and is wrapped about the cylinder. Binding wires are laid in the groove 63 in the block 62 and the block is moved to the position shown in Figs. 2 and 4. The binding wires 61 are wrapped about the fin material 60 and the ends are twisted together to hold the fin material in place. Then the parts of the apparatus are moved back to the position shown in Fig. 1 permitting the cylinder and fin assembly to be removed.

For convenience in manipulation the cylinder support 23 is rotatably mounted upon the base 20 and is held in one of a plurality of positions by means of a lever 70 having a lug 71 adapted to enter one of a series of notches 72 provided in the support 23. The lever 70 is pivoted at 73 and yieldingly pressed toward the support 23 by means of a spring 74.

The form of apparatus shown in Figs. 2 and 4 can be used with fin material having fin loops of uniform height or of different heights such as the fin material 80 shown in Fig. 6. Where fin material such as shown at 80 is used it is necessary to locate this material in a correct angular relation with respect to the cylinder as well as longitudinally. With this object in view the form of the invention shown in the remaining views has been provided. The fin material 80 includes a plurality of fins such as 81 which project the maximum distance from the base portions 82 of the fin material. Then there is a group of fins indicated at 83 which are gradually diminished in height, that is, in radial projection from the fin bases. The fin material is flattened off so to speak as will be apparent from Fig. 11 more particularly in order to permit the cylinders to be grouped together in pairs with the intake ports of each pair of cylinders closely adjacent as disclosed in the copending application of Charles F. Kettering, Serial No. 417,095, filed October 15, 1920. The fins indicated at 84 in Fig. 6

are also shorter than the fins 81 to permit close spacing of the engine cylinders. It will be observed there are two fins 85 located between fins of greater height. These fins 85 are made shorter to permit locating the valve push rods close to the cylinder. It is apparent that irregular fin material such as shown in Fig. 6 must be located in a predetermined relation with respect to the cylinder in order to have the correct position when the cylinder is mounted on the engine. Therefore this form of the invention includes means for locating this fin material with respect to the engine cylinder in a predetermined relation.

As the form of apparatus shown in Figs. 5 to 12 includes means for holding the brazing material in position and for providing a shelf for the fin material, parts of this apparatus which have functions similar to those of the apparatus shown in Figs. 1 to 4 will not be described in detail but will be designated by corresponding reference numeral with the affix "X". For example, the half-rings are designated by numerals 30^X and 31^X. This apparatus is adapted for use with a cylinder 90 having a base 91 provided with bosses 92 which are located symmetrically with respect to the cylinder. These bosses are later drilled out to receive the push rods which are located preferably symmetrically with respect to the cylinder. As it is important to line up radially the short fin loops 85 with these bosses 92, the cylinder support is provided with means for locating the bosses 92 in a predetermined relation to the support. This boss locating device includes a bifurcated member 93 having a yoke 94 adapted to be positioned between the bosses 92. The yoke is beveled at 95 and may be swung upon its trunnions 96 by lever 97 down between the bosses 92. These bosses are tapered as usual in foundry practice, therefore the yoke 94 tends to wedge itself between the bosses and cause them to be symmetrically spaced with respect to a plane passing through the axis of the cylinder and perpendicular to the axis of the trunnions 96.

The base 23^X is provided with a bracket 98 for supporting a rod 99 having a handle 100 and carrying pins 101 and 102 for holding the half-rings 30^X and 31^X in position. The parts 99 to 102 function as the lever 40 in Fig. 3. As shown in Fig. 5 the cylinder 90 is in position with the bounding sheet 45 held in position by means of the spring pressed arms 50 of the half-rings 30^X and 31^X, these spring pressed arms functioning in the same manner as described in connection with the first form of the invention. The apparatus as shown in Fig. 5 is now ready for assembling the fin material such as is shown in Fig. 6.

The half-rings 30^X and 31^X are provided

with holes 105 which are in alignment angularly with the bosses 92 when the half-rings are secured in clamping position. The half-rings are provided with other locating holes such as shown at 106.

The cylinder support 23^X is provided with a post 107 upon which is rotatably mounted a handle 108 carrying a locating plate 109 having drilled bushings 110 and 111 adapted to be placed in vertical alignment with the holes 105 and 106 respectively when the plate 109 is moved from position shown in Fig. 5 to the position shown in Figs. 10 and 11 wherein the plate is located vertically above the cylinder and substantially coaxial therewith. In order to maintain this coaxial relation, the plate 109 is provided with a central aperture 112 adapted to fit over a projection 113 which is left as a part of the cylinder head after a machine cut has been taken across the top of the cylinder.

It should be mentioned that before the fin material is assembled upon the cylinder, the cylinder is machined internally so that it may fit thoroughly snugly over the central pedestal 24 which is present in both forms of apparatus shown herein. The base of the cylinder and the top of the cylinder head are finished off in parallel relation so that these surfaces may be located correctly with respect to the shelf provided by the half-rings 30 and 31 or 30^X and 31^X as the case may be. The cylindrical surface of the cylinder to receive the fins is trued off so as to be concentric with the interior surface of the cylinder. The truing up of the exterior cylinder surface to be finned and the turning down of the stock of the cylinder head to provide the projection 113 is usually carried out in the same set-up of the cylinders in a turning lathe, therefore the projection 113 will be substantially coaxial with the cylinder. The hole 112 in plate 109 is arranged to be brought coaxial with the center column of the cylinder support therefore the projection 113 should fit within the hole 112. As the handle 108 is slideable on the post 107, the plate 109 may be lowered in the position shown in Figs. 10 and 11 and therefore the projection 113 cooperates with the plate 109 to locate the drilled bushings 110 and 111 in correct vertical alignment with the holes 105 and 106.

The fin material 80 shown in Fig. 6 is placed on the shelf provided by 30^X and 31^X and wrapped about the cylinder, the short fin loops being brought approximately into alignment with the holes 105. A pin 115 is inserted through each of the bushings 110 and the fin material is adjusted so that the pin may project through a fin loop 85 and then down through a hole 105. These locating pins will align the loops 85 with the

cylinder bosses 92 in correct angular alignment therewith.

It is desirable that the group of flattened fins 83 shall be arranged diametrically opposite the group 84 in order that, when the fin material is assembled a plane tangent to the tips of the fin loops 83 will be parallel through a plane tangent to the tips of the fin loops 84. In order to insure this parallelism, the other two pins 115 of the group shown in Fig. 7 are each inserted through a bushing 111 and through a loop of the fin material, the fin material being arranged so that one of said pins will pass through a loop having a certain relation with respect to the group of shorter fins 83 and 84.

Since the fins are not all the same height, that is, project the same distance from the center of the cylinder it is not desirable to use simply a binding wire or temporarily securing the fin into position, because as explained in the copending application of Charles F. Kettering, Serial No. 514,014 filed November 9, 1921, it is desirable that each of the fin bases 82 shall be pressed against the brazing material with substantially the same pressure in order that the bond between the cylinder and the fins may be rendered more uniform. In the assembly shown in Fig. 2, a binding wire 61 applies pressure to the fin loops of the material 60 and the fin loops themselves transmit pressure to the bases of the fin material. If binding wires are used in connection with the irregular finning the shorter fins would not at all receive pressure from the binding wires. Therefore, a number of pressure transmitting elements 120 shown in Fig. 8 are provided for assembly with the cylinder and fin assembly.

After the fin material 80 has been located as described, one of the U-shaped spacing bars 120 is placed around each of the fins which are shorter than the highest fins 81 so that a circle concentric with the axis of the cylinder would be substantially tangent to the tips of the highest fin loops and the tips of the spacing blocks 120. With this arrangement any suitable peripherally contracting binding device can be used such as binding wires 61 or a clamp 125 as shown in Fig. 9. This clamp 125 comprises a contractable split ring 126 provided with lugs 127 and 128 adapted to receive the head 129 of a screw 130 and a nut 131, respectively, as shown in Figs. 10 and 11. One or more of these clamps are placed around the spacing block 120, and the screws 129 are turned into the notch 131 to clamp the assembly temporarily together.

The pins 115 can now be removed allowing the plate 109 to be swung into the position shown in Fig. 5. The lever 100 is moved down to permit spreading apart the half-rings 30^x and 31^x. The handle 97 is

removed upwardly to cause the yoke 94 to release the base of the cylinder. Then the cylinder can be removed from the assembling fixture.

After the cylinders and fins assembled in the manner described have been removed from the assembling fixture, they are ready for subsequent treatment in order to bond the fin material permanently onto the cylinder. This treatment is described and claimed in the copending application of Charles F. Kettering, Serial No. 514,014, filed November 9, 1921 and includes heating the cylinders to a temperature above the melting points of the bonding material and below that of the fin material and the cylinder material. The heating is performed in a furnace which is arranged so that the fin material will not be unduly oxidized; and the fin material is previously coated with a protecting coating. After the bonding operation the temporary binding wires or binding clamps are removed and the cylinder is then ready for subsequent machine operations such as grinding its bore and providing valve ports in its head, and holes in the bosses 92 for the push rods.

While the form of embodiment of the invention as herein disclosed, constitutes a preferred form, it is to be understood that other forms might be adopted, all coming within the scope of the claims which follow.

What I claim is as follows:

1. Apparatus for the manufacture of finned cylinders comprising, in combination, a support adapted to receive a cylinder, means for locating the cylinder with respect to the support in a predetermined relation, means for supporting fin material about the cylinder, and means for locating the fin material with respect to the cylinder in a predetermined relation.

2. Apparatus for the manufacture of finned cylinders comprising, in combination, a support adapted to receive an engine cylinder, means for supporting a continuous strip of fin material including a plurality of fin loops placed about the cylinder, and means for locating certain of the fin loops with respect to the engine cylinder in a predetermined relation.

3. Apparatus for the manufacture of finned cylinders comprising, in combination, a support adapted to receive an engine cylinder; a pair of half-rings pivotally mounted on the support and adapted to be moved into cylinder encompassing position to clamp a sheet of bonding material around the cylinder.

4. Apparatus for the manufacture of finned cylinders comprising, in combination, a support adapted to receive an engine cylinder; a pair of half-rings pivotally mounted on the support and adapted to be moved into cylinder encompassing position to

- clamp a sheet of bonding material around the cylinder; and a toothed portion provided on each ring, one intermeshing with the other whereby the moving of one ring 5 will cause movement of the other.
5. Apparatus for the manufacture of finned cylinders comprising, in combination, a support including a central post adapted to receive an engine cylinder; a pair of half-rings pivotally mounted on the support in predetermined relation to the post and adapted to be moved into cylinder encompassing position to clamp a sheet of bonding material around the cylinder and 10 adapted to provide a locating platform for the fin material with respect to the cylinder.
10. Apparatus for the manufacture of finned cylinders comprising, in combination, a support including a central post adapted 15 to receive an engine cylinder; a pair of half-rings pivotally mounted on the support in predetermined relation to the post and adapted to be moved into cylinder encompassing position and including yielding members constructed and arranged to clamp 20 a sheet of bonding material around the cylinder and adapted to provide a locating platform for the fin material with respect to the cylinder.
30. 7. Apparatus for the manufacture of fin cylinders comprising in combination a cylinder support and means for clamping a sheet of bonding material about the cylinder and for supporting a quantity of fin material 35 placed about the cylinder.
8. Apparatus for the manufacture of fin cylinders comprising in combination a cylinder support and means for holding the cylinder in position for clamping a sheet of bonding material about the cylinder and for supporting a quantity of fin material about 40 the cylinder.
45. 9. Apparatus for the manufacture of fin cylinders comprising in combination a support for the cylinder, means for supporting a quantity of fin material about the cylinder and means for temporarily placing and positioning one or more binding wires for temporarily holding the fin material in position.
50. 10. Apparatus for the manufacture of finned cylinders comprising in combination, a support adapted to receive a cylinder, means for locating the cylinder with respect to the support in a predetermined relation, 55 and means for locating fin material with respect to the cylinder in a predetermined relation.
60. 11. Apparatus for temporarily securing to a cylinder a quantity of fin material including fins having fin bases to be joined to the cylinder, comprising in combination spacing blocks of equal height adapted to be placed against the fin bases, and clamping means adapted to bear against the spacing blocks.
12. Apparatus for temporarily securing to a cylinder a continuous strip of fin material including fins of varying height, each fin having a base, comprising in combination spacing blocks of equal height adapted 70 to be placed against the bases of fins shorter than the maximum, and clamping means adapted to bear against the spacing blocks and fins of maximum height.
13. Apparatus for the manufacture of finned cylinders comprising, in combination, a support adapted to receive an engine cylinder, including means for concentrically positioning the cylinder on the support; means secured to the support and adapted 75 to locate the cylinder on the support and prevent rotation of said cylinder relative thereto; a pair of half-rings pivotally mounted on the support and adapted to be moved into cylinder encompassing position 80 to clamp a sheet of bonding material around the cylinder and adapted to act as a locating platform for the fin material with respect to the cylinder; and means for locking 85 said half-rings in cylinder encompassing 90 position.
14. A fixture for assembling finned cylinders preparatory to the heat-treating operation comprising, in combination, a support including means for carrying a cylinder in 95 fixed relation thereto; means for clamping a sheet of bonding material about the cylinder and for supporting the fin material longitudinally relative to the cylinder; a locating plate adapted to be placed on the cylinder in fixed relation thereto; and means 100 cooperating with the locating plate, the clamping means and the fin material therebetween, for locating the fin material relative to the engine cylinder.
15. Apparatus for the manufacture of finned cylinders comprising, in combination, a support including a base and a central post over which the cylinder is adapted to fit; means supported on the base for permitting 110 the cylinder to be located in only one position relative to the base; means adapted to clamp a sheet of bonding material about the cylinder and for providing a platform for longitudinally locating the fin material relative to the cylinder, said means having a plurality of locating holes; a plate supported by the base and having holes corresponding to the holes in the bonding material clamping means, said plate being 115 adapted to be moved in position above the base post so that the holes thereof are in alignment with the holes in the clamping means; and pins adapted to be inserted in the holes of the plate and clamping means 120 and to extend adjacent to the fin material for locating the fin material relative to the engine cylinder.
16. Apparatus for the manufacture of finned cylinders comprising, in combination, 125

a cylinder support; means for clamping a sheet of bonding material about the cylinder and for supporting a quantity of fin material placed about the cylinder; and means
5 adapted to be moved into proximity with the fin material and provided with means for temporarily holding binding devices in spaced relation with the fin material while

said binding devices are secured about the fin material.

In testimony whereof I hereto affix my signature.

CHARLES L. LEE.
